CLAIM

The ornamental design for button for small appliances as shown and described.

DESCRIPTION

FIG. 1 is a front view of the button for small appliances, showing our new design.

FIG. 2 is a front perspective view of the button for small appliances.

FIG. 3 is a mirror image side view of the button for small appliances.

FIG. 4 is a front view of the button for small appliances in a condition of use.

FIG. 5 is a top perspective view of the button for small appliances in another condition of use; and,

FIG. 6 is a front perspective view of the button for small appliances in another condition of use.

The broken line portions are included to show environmental structure only and form no part of the claimed design.

1 Claim, 6 Drawing Sheets
